Patented Aug. 7, 1962

193,331

AUTOMOBILE BUMPER GUARD

Eli L. Tarazi, 4436 Franklin Ave., Hollywood, Calif.

Filed July 10, 1961, Ser. No. 65,866

Term of patent 7 years

(Cl. D14—6)

I claim:

The ornamental design for an automobile bumper guard, as shown.
